COMBINED TOOTHBRUSH AND PASTE HOLDER AND CUP AND MOUTHWASH DISPENSER

Marilyn S. Powers, 14893 Dasher Ave.,
Allen Park, Mich. 48101

Filed Apr. 8, 1968, Ser. No. 11,362

Term of patent 14 years

Int. Cl. D6—01

U.S. Cl. D33—27

FIG.1

FIG.5

FIGURE 1 is a perspective view of a combined toothbrush and paste holder and cup and mouthwash dispenser showing my new design.

The broken line representation of a toothbrush, toothpaste tube and a cup in FIGURE 1 is for purposes of illustration only.

I claim:

The ornamental design for a combined toothbrush and paste holder and cup and mouthwash dispenser, substantially as shown and described.
